UNITED STATES PATENT OFFICE.

ARTHUR F. HAINSWORTH, OF LEEDS, ENGLAND.

CRANE.

1,328,793.

Specification of Letters Patent. Patented Jan. 20, 1920.

Application filed August 18, 1917. Serial No. 186,885.

To all whom it may concern:

Be it known that I, ARTHUR F. HAINSWORTH, a subject of George V, King of England, and a resident of Ivy Dene, 5 Bramley, Leeds, Yorkshire, England, have invented a new and useful Improvement in Cranes, of which the following is a specification.

My invention is for the raising and lowering of derrick or crane jibs and at the same time keeping the load practically level, thus saving power when lifting the jib.

The derrick or jib-raising barrel may be driven from the hoisting barrel by means of 15 sprocket chains or toothed gearing giving the required ratio. As shown, a sprocket chain is used.

On the derrick or jib-raising barrel shaft is fitted a Weston plate or similar clutch 20 brake which insures perfect safety of the jib and also makes it impossible for the jib to run down. The parts are arranged so that the amount of brake action on the clutch is in direct proportion to the load on 25 barrel.

In order that my said invention may be more fully understood, I shall now proceed more particularly to describe the same, and for that purpose shall refer to several figures 30 in the drawings forming a part hereof, the same letters of reference indicating corresponding parts in all of the figures.

Figure 1 is a side elevation of a machine constructed according to this invention.

Fig. 2 is an end elevation of the hoisting mechanism and the base which supports the jib.

Fig. 3 is a side elevation of the jib-raising barrel and pawl and ratchet wheel.

Fig. 4 is a side elevation of the derrick or jib-raising barrel, and

Fig. 5 is a longitudinal section thereof showing the screw to give thrust on friction plates of ratchet wheel.

A, is the hoisting barrel which is keyed 45 to a shaft A¹ carried in a frame A². The shaft A¹ also has at one end of it a gear A³ operated by a pinion A⁴ carried on the power shaft from which power is derived to 50 drive the mechanism. In this frame A² is mounted a shaft or rod a on which runs an idler pulley b¹. C is a clutch of ordinary construction by means of which the barrel A is connected to a sprocket D which turns 55 on the shaft A¹, this construction being such that when the clutch is thrown in the proper

direction the sprocket D will be rotated, otherwise the sprocket will run free. The clutch lever itself is mounted on the end of a rock shaft suitably mounted from one side 60 of the frame A² and having at its farther end an arm c¹ attached to a lever handle c², these parts being constructed in any ordinary way so that by throwing the handle c² one way or the other the clutch will be 65 thrown either in or out as occasion may require.

The sprocket D is connected by a suitable chain d with a sprocket D¹ mounted on the end of the jib-raising barrel shaft E. This 70 shaft E is shown in detail in Fig. 5. The shaft itself is partly threaded as at E¹ and carries at its farther end a gear E². On the shaft E and free to move with relation thereto is a ratchet F which is separated from the 75 sprocket D¹ by means of a friction piece F¹ keyed to the shaft together with a nut and set nut f of usual character, this construction being such that the part F¹ serves as an abutment against which the ratchet may 80 be held by means of the drum or barrel F². This drum F² is threaded on its interior so that the pull from the jib raising rope moves it along the screw and jams it hard against the friction piece. The drum in moving in 85 this direction has automatically thrown the pawl k, to be hereinafter referred to, into gear so that the ratchet is held and consequently the jib is prevented from running down. Upon the rotation of the shaft E in 90 the same direction, however, the tendency will be for the drum to be moved away from contact with the ratchet.

G is the jib. It carries at its upper end a pulley g over which runs the hoisting rope 95 g¹ which passes down and around the hoisting drum A. From the top of the jib G runs downward a rod H carrying at its lower end a fork h in which is mounted a pulley J. Around this pulley passes the jib-raising 100 rope j. One end of this rope is attached to a hook f¹ mounted on the drum F² while the other end is fixed to the base which supports the jib. The drum is provided with a series of grooves, preferably arranged as shown in 105 the form of a helix so that at certain portions of the wind more rope will be drawn up than at other portions.

The ratchet wheel F is engaged, at times, by a pawl k carried by a hub mounted on 110 the shaft K, said hub having an interiorly threaded sleeve k¹ receiving a set screw k²

bearing at its inner end on a plate k^2 interposed between the inner end of said screw and hub and said shaft K, so that by turning in the said set screw k^4 , the said pawl 5 k will be frictionally connected with said shaft so as to turn therewith, this construction, however, permitting said shaft to turn independently of said pawl. The shaft K is mounted on the frame A² near one end 10 and in the standard A⁵ at the other end, the said standard A⁵ also carrying one end of the shaft E. On the shaft K, near the standard A⁵, is mounted a pinion k^1 in mesh with the gear E² on the jib shaft E, so that 15 the shaft K will be given a movement from the said shaft E and will tend to give a corresponding movement of the pawl k . Owing, however, to the frictional engagement between the said pawl k and its shaft K this 20 movement will be only a limited and non-positive one, the construction being such that the pawl will be held against the ratchet wheel F when the pinion k^1 is rotated in one direction by the gear E², while when the 25 movement of said gear E² is reversed said pawl will be thrown out of engagement with the said ratchet wheel F.

In practice the ropes g^1 and j are wound reversely upon their respective barrels so 30 that, for example, while the rope g^1 is being wound up, the rope j is being released. Thus the load carried by the rope g^1 may be maintained at a substantially horizontal position, and when the rope g^1 is lowered the 35 jib may be raised.

The clutch C is used to engage or disengage the sprocket D as occasion may require.

It will be seen that the ratchet is firmly 40 held by the pawl as the jib drum is lowering, and hence becomes the stationary element of a friction clutch of which the part F² is a member, and when the shaft E is rotated in the other direction the part F¹ 45 which is keyed to the shaft E causes the ratchet to move in the same direction with it, throwing the pawl out of engagement with the ratchet by means of the pinion k^1 and separating F² from the ratchet. Thus 50 in the lowering of the jib the pawl is driven into mesh with the rotating wheels, while in the hoisting of the jib the pawl is automatically thrown out of mesh.

Other forms of clutch of this general character may be substituted for that shown and

other changes in the construction of the apparatus may be made without departing from the spirit of my invention.

What I claim as my invention is -

1. In a crane, the combination with a 60 jib, of a jib drum, a hoisting drum having a disconnectible gearing connection with said jib drum so that said drums may be simultaneously rotated, if desired, or so that said hoisting drum may rotate independently of said jib drum, a shaft on which said jib drum is mounted, and with which shaft said drum has a screw threaded connection, a friction piece splined to said shaft, and a ratchet wheel interposed between said drum and said friction piece. 65

2. In a crane, the combination with a jib, of a jib drum, a hoisting drum having a disconnectible gearing connection with said jib drum so that said drums may be 70 simultaneously rotated, if desired, or so that said hoisting drum may rotate independently of said jib drum, a shaft on which said jib drum is mounted, and with which shaft said drum has a screw threaded connection, a friction piece splined to said shaft, a ratchet wheel interposed between said drum and said friction piece, a gear wheel 75 rotating with said jib drum shaft, a pinion with which said gear wheel meshes, a shaft carrying said pinion, and a pawl having a frictional connection with said last-named shaft and which may be thrown into or out of engagement with said ratchet wheel according to the direction of rotation of said 80 jib drum shaft.

3. In a crane, the combination with a hoisting drum, of a jib drum having a disconnectible gearing connection with said hoisting drum so that said jib drum may be 85 operated simultaneously with said hoisting drum or independently thereof, a shaft on which said jib drum is mounted and with which it has a screw connection so that it may be moved endwise of said shaft, a 90 ratchet wheel mounted on said jib drum shaft and having a clutch connection therewith so that it may rotate with said shaft or independently thereof, a pawl coöperating at times with said ratchet wheel to prevent rotation of the same, and means, operated from said jib drum shaft, whereby said pawl may be thrown into or out of engagement with said ratchet wheel. 105

ARTHUR F. HAINSWORTH.
